SHIPPING CASE

Filed Feb. 18, 1949

A perspective view of a wooden structure, likely a storage box or cabinet. The structure is made of vertical wooden slats. The top edge is labeled 15. On the left side, there is a vertical panel with a horizontal slot labeled 22. A vertical post labeled 25 supports this panel, and a horizontal brace labeled 26 is attached to the post. A vertical panel labeled 27 is attached to the post 25. The front panel of the structure is labeled 20. The right side of the structure features a vertical panel labeled 10. A vertical post labeled 16 is attached to the top edge of the panel 10. A horizontal brace labeled 17 is attached to the post 16. The bottom edge of the structure is labeled 11. The label 'Fig. 1.' is written in the top left corner of the drawing.

This technical drawing illustrates a cross-section of a composite structure, likely a panel or frame. It features two main panels, each with a central vertical column and a horizontal base. The left panel includes internal components labeled 21, 22, 23, 24, and 20. The right panel includes internal components labeled 16, 17, 18, 19, 14, and 12. Labels 10, 13, 15, 25, 26, and 31 are also present, indicating various parts of the structure. The drawing uses hatching to distinguish different materials or layers within the panels.

SHIPPING CASE

Peter Baar and Arthur J. Boeve, Sr.,
Holland, Mich.

Application February 18, 1949, Serial No. 77,128

2 Claims. (Cl. 217—56)

1

This invention relates to receptacles, and more particularly to a receptacle or case for storing and shipping goods therein.

The object of the invention is to provide a quickly-detachable cover for shipping cases, such as egg cases and the like.

Another object of the invention is to provide a cover or lid adapted to be readily and detachably secured to a container, such as crates for eggs, butter, cheese, and similar containers, which are repeatedly shipped back and forth.

A further object of the invention is to provide a shipping case which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a perspective view of the shipping case according to the present invention;

Figure 2 is a central longitudinal vertical sectional view of the case, with the sealing member removed;

Figure 3 is an enlarged fragmentary elevational view of the sealing end of the case;

Figure 4 is an enlarged sectional view of a modified sealing end for the case;

Figure 5 is a view showing the device of Figure 4, but with the ends of the seal reversed.

Referring in detail to the drawings, the numeral 10 designates an open-topped shipping case for storing and shipping eggs, butter, and the like. The case 10 includes a horizontally-disposed bottom wall 11, a pair of vertically-disposed, spaced, parallel side walls 12, and a pair of vertically-disposed, spaced, parallel end walls 13 and 14.

A flat lid or cover 15 is adapted to be supported by the side and end walls for closing the open top of the case and the cover 15 is detachably secured to the case, Figures 1 to 3, inclusive. For fastening the cover 15 to the case, a flange 16 is arranged transversely with respect to one end of the cover 15 and is dependably carried by or secured thereto. The flange 16 is provided with a longitudinally-extending, arcuate cut out 17. Arranged adjacent the top of the end wall 14 and secured thereto is a horizontally-disposed cover member 18 which is shaped to define an arcuate tongue 19 which seats in the cutout 17 when the cover 15 is arranged on the case. The other end wall 13 has secured thereto a horizontally-disposed support member 20 which is provided with

2

a bore or opening 21. The bore 21 extends angularly through a portion of the support member 20 and then extends vertically, Figure 2. A cross-bar 22 provided with a recess or socket 23 is secured to the other end of the case 15 and rests on the support member 20 when the cover is on the case. A vertically-disposed bore 24 communicates with the recess 23 and also registers with the bore 21 in the support member 20.

In using the device of Figures 1 to 3, the cover 15 is placed on the case with the tongue 19 seated in the cutout 17. Then a suitable sealing member 25, which includes a head 26 and a sealing strap 27, is arranged in engagement with the other end of the cover and case. The sealing member is arranged so that its head 26 seats in the recess 23 in the cross-bar 22 and a portion of the sealing strap 27 projects through the registering bores 21 and 24, whereby the cover 15 will be maintained or held on the case until the sealing member 25 is broken. The case 10 can be readily carried by gripping the lower horizontal portion of the flange 16 and the support member 20.

In Figures 4 and 5, the case is provided with a modified sealing end. There the end wall 13 has secured thereto a horizontally-disposed support member 28 which is provided with a longitudinally-extending cut-away portion 29 and the member also includes a vertically-disposed bore 30. The cover 15 has its end cut away, as at 31, and secured to the under surface of the cover 15 is a cross-bar 32 which is also cut away, as at 33. The cross-bar 32 is provided with a vertically-disposed bore 34 which registers with the bore 30 in the support member 28. In using the assembly of Figure 4, the cut-away portions 31, the cover 15, and the cut-away portion 33 of the cross-bar 32 provide a space for receiving therein the head 26 of the sealing member 25 so that a plurality of cases may be safely stacked on top of each other without damaging the sealing member 25. The cut-away 29 in the support member 28 enables the user to readily separate or lift the cover 15 from the case. In Figure 5, the sealing member 25 is inverted so that its head 26 is positioned below the support member 28 and the cut-away portions 31 and 33 prevent damage to the sealing strap 29.

As many embodiments may be made of this inventive concept, and as many modifications may be made in the embodiment hereinbefore shown and described, it is to be understood that all matter herein is to be interpreted merely as illustrative and not in a limiting sense.

We claim:

1. In a shipping case, an open-topped box comprising a pair of vertically-disposed, spaced, parallel side walls, a pair of vertically-disposed end walls extending between said side walls and secured thereto, a horizontally-disposed cover supported by said side walls and end walls, means for detachably securing said cover to said end walls, said means comprising a flange provided with a longitudinally-extending arcuate cutout arranged transversely with respect to an end of said cover and secured thereto, a horizontally-disposed cross-member secured to the outer surface of one of said end walls, said cross-member being shaped to define a curved tongue for insertion in the cutout in said flange, and means for releasably securing the other end of said cover to said case, said last-named means comprising a cross-bar provided with a vertically-disposed bore dependingly carried by the other end of said cover, there being a recess arranged in said cross-bar and communicating with said bore for receiving therein a head of a sealing member, a horizontally-disposed support member secured to the exterior of the other of said end walls, there being a bore arranged in said support member and coacting with the bore in said cross-bar for receiving a portion of a sealing strap therein.

2. In a shipping case, an open-topped box comprising a pair of vertically-disposed, spaced, parallel side walls, a pair of vertically-disposed end walls extending between said side walls and secured thereto, a horizontally-disposed cover supported by said side walls and end walls, means for detachably securing said cover to said end

walls, said means comprising a flange provided with two longitudinally-extending arcuate cutout arranged transversely with respect to an end of said cover and secured thereto, a horizontally-disposed cross-member secured to the outer surface of one of said end walls, said cross-member being shaped to define a curved tongue for insertion in the cutout in said flange, and means for releasably securing the other end of said cover to said case, said last-named means comprising a cross-bar arranged transversely with respect to the other end of said cover and dependingly carried by the latter, a horizontally-disposed support member secured to the other end wall of said case, there being a vertically-disposed bore arranged in said support member and said cross-bar, said bores registering with each other and adapted to receive therein a portion of a sealing strap.
